Filed Jan. 31, 1968, Ser. No. 10,375

Term of patent 14 years

Int. Cl. D30—99

U.S. Cl. D30—41

FIG. 3

FIG. 1 is an end elevation of a poultry case embodying my new design,

FIGURE 2 is a fragmentary top perspective view of the poultry cage and

FIGURE 3 is an end perspective view taken diametrically opposite from FIGURE 2 and broken away intermediate its ends for convenience of illustration.

In FIGURE 3 of the drawings it is to be understood that the structure shown in the broken away portions is continued throughout the entire length of the poultry cage.

The dominant features of my design are shown in full lines.

I claim:

The ornamental design for a poultry cage, as shown and described.
